UNITED STATES PATENT OFFICE.

JOHN H. PARMELEE, OF BRIDGEPORT, CONNECTICUT, ASSIGNOR OF ONE-HALF TO AARON W. WALLACE, OF SAME PLACE.

HAME-FASTENER.

SPECIFICATION forming part of Letters Patent No. 423,529, dated March 18, 1890.

Application filed December 17, 1889. Serial No. 334,036. (No model.)

To all whom it may concern:

Be it known that I, JOHN H. PARMELEE, a citizen of the United States, residing at Bridgeport, in the county of Fairfield and State of Connecticut, have invented certain new and useful Improvements in Hame-Locks; and I do hereby declare the following to be a full, clear, and exact description of the invention, such as will enable others skilled in the art to which it appertains to make and use the same.

My invention has reference to hame-locks; and it consists in the details of construction and combination of elements, such as will be hereinafter fully set forth, and then specifically designated by the claims.

In the accompanying drawings, Figure 1 is a perspective of my improvement in position on a pair of hames, the latter being broken away; Fig. 2, a detail sectional elevation of the locking member of my hame-lock; Fig. 3, a sectional elevation of my improvement as it appears when the hames are locked; Fig. 4, a sectional elevation similar to Fig. 2, but showing the locking member slightly modified in construction; and Fig. 5, a bottom view of my improvement, showing the link of chain which is engaged by the dog drawn up within the channels in the cross-bar to permit the withdrawal of said dog.

Similar letters denote like parts in the several figures.

A B represent a pair of hames provided at their lower ends with the usual rings C D.

E is an S-hook pivoted at one end around the ring C, a chain F being attached to the other end.

G is a box whose rear end is curled around the ring D, and whose central portion is open from top to bottom. At the forward end of this box is a cross-bar H, which is curved in cross-section on the inside, so as to afford a smooth and free bearing, over which the chain F may be drawn, as will be presently set forth. Within this box a dog I is pivoted at J, so as to swing freely, the heel of said dog being provided with a weight L, whose func-

tion is to counterbalance said dog, so that the nose thereof is always normally against a point a on the bottom of the cross-bar. Of course a spring K, arranged between the heel of the dog and the top wall of the box, as seen at Fig. 4, may be used instead of the weight L; but I prefer the latter, since the action and reaction of the spring are too quick. 55

The bottom of the cross-bar H on each side of the point a is cut away to form channels b, so that in unlocking the hames it is merely necessary to roll the link which the dog engages up into said channels, and thus leave 60 the nose of the dog free to be thrown down and away from the cross-bar, as will be readily understood by reference to Fig. 5. This peculiar construction of the cross-bar is a very important feature of my invention, since if 65 said bar were perfectly plain on the bottom the dog and interlocked link could not possibly be disengaged unless the chain were first pulled down by main strength, so as to permit said dog to be swung freely from within the 70 link.

The operation of my improvement is as follows: The chain is passed through the box from above, the dog being forced away from the cross-bar, a small nub M on the bottom 75 of the dog affording a hold whereby said dog may be conveniently operated and simply pulled down until the hames are sufficiently tightened. The chain will readily pass underneath the dog, the nose of the latter automatically engaging the links of the chain, so as to secure the same as against any slipping upward. 80

I claim—

1. In a hame-lock, the combination of a box pivotally swung on one of the hames, said box having at the front end a cross-bar provided on its under side with an elevated point and channels on each side of said point, a dog pivoted within the sides of said box 90 and having a weighted heel, and a link chain suspended from the other hame, substantially as set forth.

2. In a hame-lock, the combination, with

the box having a cross-bar at the front end, of a dog pivoted within said box, the nose of said dog extending forward beneath the cross-bar, while the heel of the dog is weighted, whereby said nose is normally held in elevation against the bottom of said cross-bar, and a link chain adapted to be engaged by said nose, substantially as shown and described.

In testimony whereof I affix my signature in presence of two witnesses.

JOHN H. PARMELEE.
